UNITED STATES PATENT OFFICE.

JOHN F. METTEN, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

SYSTEM OF MARINE STEAM-TURBINES.

1,235,990.

Specification of Letters Patent. Patented Aug. 7, 1917.

Application filed September 9, 1915, Serial No. 49,662. Renewed March 31, 1917. Serial No. 159,024.

To all whom it may concern:

Be it known that I, JOHN F. METTEN, a citizen of the United States, residing at Philadelphia, in the county of Philadelphia and State of Pennsylvania, have invented 5 certain new and useful Improvements in Systems of Marine Steam-Turbines, of which the following is a full, clear, and exact specification.

10 This invention relates to a system of marine steam turbines for driving multiple screw ships at economical cruising speeds. The invention is especially applicable to war vessels which necessarily do most of 15 their running at cruising speeds, but must have provision for driving at full speed when desired. Steam turbines, driving propeller shafts directly are satisfactory at higher speeds and powers, but if the vessel 20 is run at cruising speeds below the designed maximum speed, with high speed and high power turbines, there is a material reduction in efficiency. This is due to the reduced blade speed at low powers which involves 25 corresponding loss in hydraulic efficiency, and also to the "drowning" effect on the low pressure blades at the exhaust end, which practically become inoperative.

It is the object of this invention to overcome 30 these disadvantages, and also to provide an improved combination of main and cruising units wherein at cruising speeds, but one-half of the condensing plant and pumps are required, instead of requiring 35 use of the entire condensing plant and pumps, as in previous systems. By enabling the ship to be driven at cruising speeds with only one-half the full condenser plant and pumps in operation, a very 40 decided saving in steam is accomplished.

According to the present invention, for a twin screw shaft installation I provide a main unit on each shaft in combination with a cruising unit geared to one shaft and, at 45 cruising speeds, exhausting into the main unit on the other shaft. Thus, at cruising speeds, the ship is propelled by two shafts, one of which is driven by the geared cruising unit with the main unit on this shaft 50 revolving in vacuum, and the other shaft being driven through the main unit by the steam exhausted by the cruising unit. The high pressure high speed cruising unit can thus operate at a very high efficiency, and there 55 will be a complete expansion of the steam

in this and the series connected main unit. At full powers, the geared cruising unit is simply disconnected from its propeller shaft by a clutch and both main units are then supplied by high pressure steam in the usual 60 manner.

In the accompanying drawings is shown an arrangement intended for a twin screw vessel, but the invention is equally applicable to four shafts. 1 and 2 are the main 65 units directly connected to propeller shafts 3 and 4. These units may either be of the impulse or reaction type and each consists of an ahead and an astern portion contained in the same casing and exhausting into 70 condensers 5, 6, respectively. To one of the shafts, as for example, shaft 3, is connected a high speed cruising unit 7 through reduction gear 8 and a quick connecting clutch 9. The unit 7 is preferably a high speed high 75 pressure turbine, but any other high speed unit, such as a reciprocating engine, could be used in connection with the reduction gear. The clutch 9 may be of the sliding jaw type, but is preferably of the hydraulic 80 friction type heretofore invented by me.

When running at high speed, the clutch 9 is open and the cruising turbine 7 is inoperative and idle, steam being supplied directly to the initial high pressure stages of turbines 1 and 2 by pipes in parallel controlled by valves 24. At cruising speeds, when clutch 9 is closed, steam is supplied directly to cruising turbine 7 by a pipe controlled by valve 15, valves 24 being closed. Under 90 these conditions, the turbine 1 will be driven idly, through the reduction gear 8 and the clutch 9, and the exhaust steam from turbine 7 will pass by pipe 10 through valves 11 and 14 to one or the other of inlets 12, 13 95 and turbine 2, depending upon the particular cruising speed desired. When the steam is admitted directly to turbine 2 through pipe 12 at one of the intermediate wheel stages, the speed will be higher than where 100 the steam is admitted to turbine 2 through pipe 13 at the initial wheel stage. The steam supply to cruising unit 7 will be correspondingly varied so that the speeds of both shafts will be alike. The valve 14 is 105 so constructed as to have two positions and admit steam either through inlet 12 or inlet 13 as may be desired. 16 is the circulating pump for turbine 1, and 17 is the air pump, which are shut down while cruising, turbine 110

1 revolving idly in the vacuum produced by the air pump 27 belonging to turbine 2. 18 is a small pipe which connects the discharge sides of circulating pumps 16 and 19 to insure 5 a slight circulation of water through the condenser 5 when pump 16 is shut down. 20 is a cross connecting pipe connecting the bottoms of condensers 5 and 6 for draining condenser 5 and also for maintaining a 10 vacuum in condenser 5 in case the cross connection 22 should be omitted. Preferably, pipe 22 is provided for this purpose and is controlled by valve 23; also, there is a valve in pipe 18 for controlling the amount 15 of circulating water passing from pump 19 to condenser 5. The pipe 22 is of sufficient size to pass the steam from turbine 1 to condenser 6 during light maneuvering when cruising turbine 7 is temporarily disengaged. At this time, the throttle valves 24 are used to supply steam direct to turbines 1 and 2 for forward running, and throttle valves 25 for reverse running. By this arrangement of cross connected pipe 22, 25 it will be seen that under certain conditions one pump and condenser, as 19 and 6, can be used alone. At this time the air pump 27 will also suffice to maintain the vacuum in both condensers. In running at full 30 power, the pumps 16 and 17 will be started and the plant then operated in the usual manner.

By the arrangement of high speed geared cruising unit on the one shaft combined 35 with the main unit on the other shaft, the quantity of steam passed through the latter may be doubled as compared with what would otherwise be the case with the usual 40 cruising arrangements wherein a high pressure turbine directly coupled on one shaft is connected into a low pressure turbine directly coupled on the other shaft. It will be understood that the size and power of the cruising unit, as well as the particular 45 ratio of gear reduction, will be proportioned according to the requirements of the particular installation to be made, but in general, it will be seen that at cruising speeds the steam will be so utilized in the geared 50 unit and in the main unit, that both the power shafts will turn at the same number of revolutions and thereby develop the same power. Such an arrangement will have the 55 advantage of utilizing the full expansion of the steam, and also in not requiring so much steam to operate the auxiliaries, such as the circulating pump and the air pump. It has been found that one air pump and one circulating pump can, without increased consumption of power, take care of both the main unit receiving the exhaust steam from the geared unit and also maintain the vacuum in the idle main unit.

Various modifications and changes may be made in the specific construction herein de-

scribed without departing from the scope of the appended claims.

Having thus described my invention, what I declare as new and desire to secure by Letters Patent of the United States is:—

1. In a marine propulsion arrangement, a plurality of shafts, a full power propelling unit on each shaft, means for supplying power to said units for full power, a high speed cruising unit geared to one of said shafts, and means for passing the exhaust from said high speed cruising unit to the full power unit on the other shaft to produce approximately equal powers on said shafts for cruising speed. 70

2. In a marine propulsion arrangement, a plurality of shafts, a full power propelling unit on each shaft, means for supplying full power to each unit, a high speed cruising unit connected by reduction gearing to one of said shafts, and means for passing the exhaust from said high speed cruising unit to the full power unit on the other shaft to produce approximately equal powers on said shafts for cruising speeds. 85

3. In a marine propulsion arrangement, a plurality of shafts, a full power propelling unit on each shaft, means for supplying power to said units for full power, a high speed cruising unit geared to one of said shafts, means for passing the exhaust from said high speed cruising unit to the full power unit on the other shaft to produce approximately equal powers on said shafts for cruising speed, and means for disconnecting said cruising unit and its gearing at full power. 95

4. In a marine propulsion arrangement, a plurality of shafts, a full power propelling unit and condenser plant for each shaft, a cruising unit connected to one of said shafts, means for passing the exhaust from said cruising unit through the full power unit and the condenser plant for the other shaft. 105

5. In a marine propulsion arrangement, a plurality of shafts, a full power propelling unit on each shaft, a condenser plant for each unit, a cruising unit connected to one of said shafts, means for passing the exhaust from said cruising unit through the full power unit on the other shaft, and means for condensing the exhaust from said latter unit in one of said condenser plants when the other is idle. 115

6. In a marine propulsion arrangement, a plurality of shafts, a full power propelling and condensing unit for each shaft, a cruising unit connected to one of said shafts, means for passing the exhaust from said cruising unit through the full power unit on the other shaft, and a cross connection between the low pressure ends of said main units. 125

7. In a marine propulsion arrangement, a plurality of shafts, a full power propelling 130

and condensing unit for each shaft, a cruising unit connected to one of said shafts, means for passing the exhaust from said cruising unit through the full power unit on the other shaft, and means for condensing the exhaust in one of said condensing units and for draining both when one condensing unit is shut down.

8. In a marine propulsion arrangement, a plurality of shafts, a full power propelling and condensing unit for each shaft, a cruising unit geared by a reduction gear to one of said shafts, a quick connecting clutch be-

tween said reduction gear and said shaft, means for leading the exhaust of said cruising unit to the main unit on the other shaft, a plurality of inlets to said latter unit for varying the power, and a connection between the idle and the active condenser units.

In testimony whereof I affix my signature, in presence of two witnesses.

JOHN F. METTEN.
